UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,459, dated September 13, 1881.

Application filed August 9, 1881. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

The carpet is divided into two prominent parallel bands, A and B, which are divided by 15 an ornamental stripe, a. The band A contains, on a doubly-arched border, b, a large bouquet, C, of roses and leaves, and also a smaller bouquet, D, as shown. The band B is decorated with a rosette, d, which carries a conventional 20 bouquet, E, that throws its branches in opposite directions above an ornamental band, e. In the band B is also another ornament, F, which, on a decorative pedestal, f, has a stem, g, that carries branching leaves h h.

I claim—

1. The design for carpets, consisting of the figure C, substantially as shown. 25
2. The design for carpets, consisting of the figure D, substantially as shown.
3. The design for carpets, consisting of the figures A C D a b, substantially as shown. 30
4. The design for carpets, consisting of the figure E, substantially as shown.
5. The design for carpets, consisting of the figures F f g h, substantially as shown. 35
6. The design for carpets, consisting of the figures B d E e F f g h, substantially as shown.
7. The design for carpets, consisting of the figures A C D a b B d E e F f g h, substantially as shown.

HENRY HORAN.
